UNITED STATES PATENT OFFICE.

JOHN B. BATT, OF WILLIAMSVILLE, ASSIGNOR OF ONE-HALF TO LORENZ GEBHARD, OF BUFFALO, NEW YORK.

FREIGHT-CAR DOOR.

SPECIFICATION forming part of Letters Patent No. 352,731, dated November 16, 1886.

Application filed August 30, 1886. Serial No. 212,146. (No model.)

To all whom it may concern:

Be it known that I, JOHN B. BATT, of Williamsville, in the county of Erie and State of New York, have invented a new and useful Improvement in Freight-Car Doors, of which 5 the following is a specification.

This invention has for its object to provide freight-cars with swinging doors or gates arranged inside of the car and adapted to close 10 the entrance in the sides of the car, whereby grain, coal, and other material in bulk can be conveniently transported and confined in the car independently of the sliding doors, which are arranged on the outside of the car, the 15 swinging gates or doors being so constructed that they can be readily swung out of the way when not required.

The invention consists of the improvement, which will be hereinafter fully set forth, and 20 pointed out in the claims.

In the accompanying drawings, Figure 1 is a fragmentary side elevation of a freight-car provided with my improvement. Fig. 2 is a horizontal section in line *x x*, Fig. 1. Fig. 3 25 is a fragmentary vertical section of the inside of the car, with the swinging gate swung down out of the way. Fig. 4 is a similar view showing the swinging gate raised to close the entrance. Fig. 5 is a vertical section in line *y y*, 30 Fig. 1, the swinging gate being swung down. Fig. 6 is a vertical section in line *w w*, Fig. 5.

Like letters of reference refer to like parts in the several figures.

A represents one of the sides of an ordinary 35 freight-car, *B* the floor, *C* the usual entrance formed in the side of the car, and *D* the sliding door, which is arranged on the outside of the car in the usual manner for closing the entrance to the car.

E represents a swinging door or gate arranged inside of the car, and adapted to close the entrance *C*, or the lower portion thereof. The gate or door *E* is hinged at its bottom to the floor of the car, between the vertical 45 posts *ff*, on opposite sides of the entrance *C*, so that the gate can swing outwardly or inwardly between the posts *ff*. The gate *E* is preferably constructed of sheet-iron, and is secured at its lower end to a rod, *g*, the ends

of which are journaled in holes *g'*, formed in 50 the lower edges of the posts *f*.

H H represent pivoted wings or stops, which are seated in vertical slots *h* formed in the posts *f*. The slots *h* open outward into the entrance or space between the two posts *f*, and 55 extend into the posts far enough to allow the stops, when moved back into the slots, to be concealed by the posts, and permit the gate to swing past the posts without coming in contact with the stops. The stops *H* are pivoted in 60 the slots *h* at their lower ends, and the stops preferably increase in width gradually toward their top. Upon turning the stops *H* on the pivots outwardly the upper outer edges of the stops will project into the space between the 65 two posts on opposite sides of the entrance *C*, and prevent the gate *E*, when raised, from swinging outwardly past the stops, as shown in Fig. 2.

The stops *H* are each provided near their 70 upper ends with a stud or pin, *i*, which projects through a curved slot, *i'*, formed in the inner side of the posts *ff*, and extending into the slots *h*. The stops *H* can be readily moved in the slots *h* forwardly and backwardly by 75 means of the studs *i*. *j* represents pivoted hooks secured to the posts *f*, and adapted to engage over the projecting ends of the studs *i* when the stops are moved outward, as shown in Figs. 1 and 2, and lock the stops in this position. When the gate *E* is raised and the stops *H* project out of the slots in the posts *f*, 80 the grain or other material contained in the car will hold the gate in a vertical position across the entrance *C* and against the stops, 85 thus closing the entrance. Upon drawing the stops *H* into the slots, when desired to unload the car, the pressure of the grain or other material in the car will force the gate outward until the outer lower edge rests upon the edge 90 of the floor, as shown in dotted lines in Fig. 5. When the gate is in this position, it forms a convenient support or bridge over which the material can descend in unloading the car. When the gate *E* is not required to be used, it 95 is swung inwardly until it rests upon the floor, as shown in full lines in Fig. 5. The floor is recessed or cut away at *k* to receive the gate

and permit the gate to drop into the recess, with its upper side on a level with the floor of the car. The gate, when in this position, is entirely out of the way and does not obstruct any 5 of the floor-space of the car.

I claim as my invention—

1. In a freight-car, the combination, with the posts of the side opening and the car-floor, of a swinging door, hinged at its bottom to 10 swing between said posts inwardly to the car-floor and outwardly to the bottom of the side opening, whereby the door can be swung upon the bottom of the car-floor when not required for use, or be swung out for discharging the 15 cargo, substantially as set forth.

2. In a freight-car, the combination, with the posts of the side opening and the car-floor, of a swinging door, hinged at its bottom to swing between said posts inwardly to the car- 20 floor and outwardly to the bottom of said opening, and stops attached to said posts by pivots

arranged at right angles to the pivots of the car-door, whereby the stops can be projected into the side opening of the car, thereby preventing the door from swinging outwardly beyond 25 said stops, substantially as set forth.

3. The combination, with the posts *f*, provided in their inner faces with recesses *h*, of stops *H*, pivoted in said recesses, and a door, *E*, pivoted at its bottom to swing between said 30 posts inwardly to the car-floor and outwardly to the bottom of the side opening, whereby said stops can be projected into the side opening to bear against the outer side of the door and prevent the latter from moving outwardly 35 beyond said stops, substantially as set forth.

Witness my hand this 25th day of August, 1886.

JOHN B. BATT.
